TUYÈRE CONSTRUCTION WITH COOLING AND STEAM FEEDING MEANS

George H. Wolfe and Dorothy E. Mackenzie,
Reno, Nev.

Application August 7, 1946, Serial No. 688,882

7 Claims. (Cl. 110—182.5)

1

This invention relates to improvements in tuyères of the character used with apparatus in which high temperatures are required to be established in order to produce a desired result.

The object of the invention is to provide a tuyère for use in connection with apparatus in which high temperatures are established and which is constructed with an outer shell or chamber filled with lead, or other similar material having a low melting point, for absorbing the heat transmitted to the tuyère from the apparatus.

Additional objects and advantages of the tuyère construction will become apparent from the following description taken in connection with the accompanying drawings, wherein

Figure 1 is a side elevational view of the tuyère made in accordance with our invention and indicating by dotted lines the relative position of the several parts of the interior construction thereof;

Figure 2 is a cross-sectional view of the tuyère construction and showing the tuyère as it would be positioned in the wall of an apparatus with which it is intended to be used;

Figure 3 is a rear end view of the tuyère and showing the relative positions of the air inlet tube, the lead reservoir, and the water inlet tube of the construction; and

Figure 4 is a view of the nozzle end of the tuyère with a part broken away to indicate the relative position of the parts.

It is well known that tuyères which are used with apparatus of the type in which high temperature combustion zones are required to be established, are subjected to such extreme heat temperatures that unless they are specially protected their life and usefulness is greatly shortened.

It is also known that in the operation of a gas producer retort, which is an apparatus of the type where high temperature combustion zones are necessary to produce the results desired, the rate of gasification will be considerably increased if the temperature of the combustion zone is maintained in a constant elevated condition. Also, it is known that if the air introduced into such a gas producer apparatus through the tuyère, is in a heated state, the temperature of the combustion zone will be increased and thus the overall efficiency of the apparatus and the rate of gasification will be benefited. Another advantageous practice in the operation of such an apparatus is to admit superheated steam to the high temperature combustion zone thereof. Such steam, when introduced to the combustion zone,

can be gasified and decomposed into its basic components of carbon and oxygen. These components are suitable to form a very hot combustion zone. Hydrogen, which is a byproduct of the gasification of carbon, is also a combustible gas which can be used to produce a high temperature combustion zone.

It is an object of this invention to provide a tuyère which will be capable of withstanding the high temperatures and pressures of the combustion zones of the apparatus in which it is used.

It is another object of this invention to provide a tuyère which will be capable of withstanding the high temperatures and pressures of the combustion zones of the apparatus in which it is used.

It is a further object of this invention to provide a tuyère which will be capable of withstanding the high temperatures and pressures of the combustion zones of the apparatus in which it is used.

It is a still further object of this invention to provide a tuyère which will be capable of withstanding the high temperatures and pressures of the combustion zones of the apparatus in which it is used.

It is a still further object of this invention to provide a tuyère which will be capable of withstanding the high temperatures and pressures of the combustion zones of the apparatus in which it is used.

It is a still further object of this invention to provide a tuyère which will be capable of withstanding the high temperatures and pressures of the combustion zones of the apparatus in which it is used.

It is a still further object of this invention to provide a tuyère which will be capable of withstanding the high temperatures and pressures of the combustion zones of the apparatus in which it is used.

It is a still further object of this invention to provide a tuyère which will be capable of withstanding the high temperatures and pressures of the combustion zones of the apparatus in which it is used.

It is a still further object of this invention to provide a tuyère which will be capable of withstanding the high temperatures and pressures of the combustion zones of the apparatus in which it is used.

It is a still further object of this invention to provide a tuyère which will be capable of withstanding the high temperatures and pressures of the combustion zones of the apparatus in which it is used.

It is a still further object of this invention to provide a tuyère which will be capable of withstanding the high temperatures and pressures of the combustion zones of the apparatus in which it is used.

It is a still further object of this invention to provide a tuyère which will be capable of withstanding the high temperatures and pressures of the combustion zones of the apparatus in which it is used.

It is a still further object of this invention to provide a tuyère which will be capable of withstanding the high temperatures and pressures of the combustion zones of the apparatus in which it is used.

It is a still further object of this invention to provide a tuyère which will be capable of withstanding the high temperatures and pressures of the combustion zones of the apparatus in which it is used.

It is a still further object of this invention to provide a tuyère which will be capable of withstanding the high temperatures and pressures of the combustion zones of the apparatus in which it is used.

It is a still further object of this invention to provide a tuyère which will be capable of withstanding the high temperatures and pressures of the combustion zones of the apparatus in which it is used.

It is a still further object of this invention to provide a tuyère which will be capable of withstanding the high temperatures and pressures of the combustion zones of the apparatus in which it is used.

It is a still further object of this invention to provide a tuyère which will be capable of withstanding the high temperatures and pressures of the combustion zones of the apparatus in which it is used.

It is a still further object of this invention to provide a tuyère which will be capable of withstanding the high temperatures and pressures of the combustion zones of the apparatus in which it is used.

It is a still further object of this invention to provide a tuyère which will be capable of withstanding the high temperatures and pressures of the combustion zones of the apparatus in which it is used.

It is a still further object of this invention to provide a tuyère which will be capable of withstanding the high temperatures and pressures of the combustion zones of the apparatus in which it is used.

It is a still further object of this invention to provide a tuyère which will be capable of withstanding the high temperatures and pressures of the combustion zones of the apparatus in which it is used.

It is a still further object of this invention to provide a tuyère which will be capable of withstanding the high temperatures and pressures of the combustion zones of the apparatus in which it is used.

It is a still further object of this invention to provide a tuyère which will be capable of withstanding the high temperatures and pressures of the combustion zones of the apparatus in which it is used.

It is a still further object of this invention to provide a tuyère which will be capable of withstanding the high temperatures and pressures of the combustion zones of the apparatus in which it is used.

It is a still further object of this invention to provide a tuyère which will be capable of withstanding the high temperatures and pressures of the combustion zones of the apparatus in which it is used.

It is a still further object of this invention to provide a tuyère which will be capable of withstanding the high temperatures and pressures of the combustion zones of the apparatus in which it is used.

It is a still further object of this invention to provide a tuyère which will be capable of withstanding the high temperatures and pressures of the combustion zones of the apparatus in which it is used.

It is a still further object of this invention to provide a tuyère which will be capable of withstanding the high temperatures and pressures of the combustion zones of the apparatus in which it is used.

of an apparatus, such for instance as a gas producer retort. The tuyère is constructed in such manner that it is provided with the outer and inner steel walls 2 and 3, which are spaced apart sufficiently to provide a chamber or shell 4, and with the inner walls forming a central air duct 5. The chamber or shell 4 terminates at the rear end of the tuyère in an enlarged chamber or reservoir portion 6, which is provided with a filling opening 7. This filling opening may be provided with any suitable type of closure (not shown). Mounted within the reservoir portion 6 of the chamber or shell 4 and shaped so that they will extend through the chamber portion 4, are one or more heat conduction elements 8 which are suitably made of copper. Extending through the reservoir portion 6 of the chamber or shell, and communicating with the air duct 5, is a water supply tube 9 which is adapted to have its outer end 10 connected to a suitable water supply source.

The chamber or shell 4 and its reservoir portion 6, is intended to be filled with lead, indicated at 8, through the opening 7.

When the tuyère is to be used in connection with a gas producing retort, it is to be understood that under working conditions, the retort would be filled with carbonaceous fuels and a combustion fire zone would be established in an area within the retort adjacent to the point where the tuyère projects through the wall of the retort. When such a combustion fire zone is present within the retort, the end of the tuyère, which projects into the retort would be subjected to the very intense heat from the fire zone, and the temperature of the metal at the end of the tuyère will become elevated. The lead which is enclosed in the chamber or shell portion 4, and which extends to the nozzle end of the tuyère will thus become heated and will tend to liquefy, and the heat imparted to the lead will be conducted backwardly into the body of the lead which is contained in the reservoir portion 6. In time, all of the lead within the chamber portion 4 and reservoir portion 6, will be heated to a liquid state due to the heat which is pushed up by the lead which is in contact with the hot tip of the tuyère.

The cool air which flows through the air duct 5, of the tuyère construction, will serve as a means of dissipating the heat from the liquefied lead contained in chamber 4, and reservoir 6, and said air will thus become preheated as it passes through the tuyère so that when it enters the retort in its preheated condition it will function to better accelerate the combustion in the fire zone therein. If desired, fins (not shown), could be located on the inner side of tube 3 to increase the rate of heat transfer to the incoming air passing through tube 3. The heat from the molten lead within the chamber 4, and reservoir portion 6, will also be transmitted to the water as it passes through the tube 9 and will cause the water to be changed into superheated steam, and said steam will pass through the air duct 5, with the air and will also function to accelerate the combustion within the retort and to enrich the B. t. u. content of the gas by adding hydrogen to the gas as it is being produced.

The copper heat exchange elements 8, positioned within the chamber 4 and reservoir portion 6 of the tuyère, will also function to increase the rate of the removal of the heat from the tuyère end. As is well known, lead will melt at 621 degrees Fahrenheit, and its rate of

conduction is only nine per cent as great as copper. This being so, when the lead contained in chamber 4 at the nozzle end of the tuyère becomes liquefied, and as its liquefied area increases so that it will embody the ends of the copper elements 8, B. t. u.'s of heat will rapidly pass through the copper elements 8 to increase the area of liquid lead, and in particular to melt rapidly the lead in the reservoir portion 6. The purpose of effecting this action is to eliminate or reduce the extent of the expansion of the lead in the nozzle end of the tuyère, which if it is restrained by solidified lead in the reservoir portion, will expand and will gradually distort the portion of the exterior casing of chamber 4 which extends through the wall of the retort. By using two or more of these copper heat exchange elements in the tuyère construction it will be possible to quickly establish a molten channel of lead surrounding each copper element and the lead in the reservoir portion will become liquefied rapidly and permit a normal rate of liquid expansion in the chamber 4, and eliminate the internal thermal expansion pressure being established by the melting lead at the heated end of the tuyère.

It has been found that in operation the temperature of the lead will reach 900 to 1000 or more degrees, depending upon the size and cooling area of the shell 4, and reservoir 6. By decreasing the size and cooling area of the shell and reservoir, the temperature of lead within the tuyère will be raised and thus the degree of preheat imparted to the incoming air will be increased. Also, by increasing this area of the lead chambers the temperature imparted to the incoming air will be decreased.

Although the above description refers to a tuyère used with a gas generating apparatus, the invention is not intended to be limited to tuyères of this type. The method of heat conduction accomplished by the construction and the functioning of the tuyère to maintain proper temperature conditions within an apparatus can be used in numerous other apparatus where high temperatures are required for a desired result. For instance, the principles of the invention may be employed in fuel nozzles used in the combustion chambers of combustion motors attached to jet propulsion drives. Also such a tuyère may be used in connection with turbines and other apparatus, where liquid molten metallic heat conduction would prolong the life and effectiveness of high temperature parts and make possible operating temperatures otherwise unobtainable, or they may be used to maintain a uniform temperature throughout a passage or conduit for any desired operation.

Having now described our invention, what we claim is:

1. A tuyère comprising a cylindrical metallic body formed with an outer annular cooling jacket terminating at one end in an enlarged chamber extending upwardly to a level above the level of the tip of the tuyère, metallic heat conduction elements mounted in said cooling jacket extending down through said enlarged chamber and into said cooling jacket forward substantially to the end of said tuyère, and a filling of metallic material possessing a low melting point in the cooling jacket.

2. A tuyère comprising a metallic body formed with a central tapered longitudinal passage therethrough and having an outer annular cooling jacket terminating at one end in an enlarged

chamber extending upwardly to a level above the level of the tip of the tuyère, metallic heat conduction elements mounted in said cooling jacket extending substantially from the upper extremity of said enlarged cooling chamber to the extremity of said tuyère, a water tube extending through the enlarged chamber and communicating with the central longitudinal passage through the tuyère, and a filling of metallic material having a low melting point in the cooling jacket.

3. A tuyère comprising a cylindrical metallic body formed with a tapered central longitudinal passage therethrough and having an outer annular cooling jacket terminating at one end in an enlarged chamber extending upwardly to a level above the level of the tip of the tuyère, curved metallic heat conduction elements mounted in said cooling jacket extending substantially from the upper extremity of said enlarged chamber to the inner extremity of the tuyère, and a filling of lead in the cooling jacket.

4. A tuyère comprising a cylindrical metallic body formed with a tapered central longitudinal passage therethrough and having an outer annular cooling jacket extending at one end to the nose portion of the tuyère and terminating at the other end in an enlarged chamber extending upwardly to a level above the level of the tip of the tuyère, copper heat conduction elements mounted in said cooling jacket extending substantially from the uppermost extremity of said enlarged chamber to the extremity of the nose portion of the tuyère, and a filling of lead in the cooling jacket.

5. A tuyère comprising a cylindrical steel body formed with a tapered central longitudinal passage therethrough and having an annular outer chamber extending at one end to the nose portion of the tuyère and terminating at the other end in an enlarged reservoir portion extending upwardly to a level above the level of the tip of the tuyère, copper heat conductor elements mounted in the reservoir portion and extending in the annular outer chamber to the nose portion of the tuyère so that the heat conductor elements extend substantially from the uppermost extremity of the enlarged reservoir portion to the extremity of the nose portion of the tuyère, a water tube extending through the reservoir portion and communicating with the central longitudinal passage, and a filling of lead in the outer chamber and reservoir portion.

6. A tuyère comprising a cylindrical steel body formed with a tapered central longitudinal passage therethrough and having an annular outer cooling chamber extending at one end to the nose portion of the tuyère and terminating at the other end in an enlarged reservoir portion

extending upwardly to a level above the level of the tip of the tuyère, an opening in said reservoir portion adapted to receive a cooling medium for said cooling chamber, a plurality of copper heat conductor rods mounted in the reservoir portion and extending into the cooling chamber to the nose portion of the tuyère, so that the heat conductor rods extend substantially from the uppermost extremity of the enlarged reservoir portion to the inner extremity of the nose portion of the tuyère, a water tube extending through the reservoir portion and communicating with the central longitudinal passage, and a filling of lead in the outer cooling chamber and in the reservoir portion.

7. A tuyère comprising a cylindrical metallic body provided with a tapered central passage therethrough and formed with an outer annular chamber which extends to the end of the nose portion of the tuyère at one end and terminates in an enlarged reservoir portion extending upwardly to a level above the level of the tip of the tuyère at the other end, a plurality of heat conductor elements positioned within the reservoir portion and extending into the annular chamber to the nose portion of the tuyère so that the heat conductor elements extend substantially from the upper extremity of the reservoir portion to the inner extremity of the nose portion of the tuyère, a water tube extending through the reservoir portion and communicating with said central passage through the tuyère, and a metallic material filling said outer annular chamber including the reservoir portion thereof and which has a low melting point and a rate of heat conduction less than the said heat conductor elements.
